UNITED STATES PATENT OFFICE.

WILLIS STETSON WILLIAMS, OF MANCHESTER, ENGLAND.

AERIAL MACHINE.

1,150,650.

Specification of Letters Patent.

Patented Aug. 17, 1915.

Application filed September 20, 1913. Serial No. 790,874.

To all whom it may concern:

Be it known that I, WILLIS STETSON WILLIAMS, a subject of the King of Great Britain and Ireland, residing at 28 Park avenue, 5 Alexandra Park, Manchester, Lancashire, England, have invented certain new and useful Improvements in and Relating to Aerial Machines, of which the following is a specification.

10. This invention relates to aerial machines of the rigid type having aerostats, and particularly to that type in which the body of the machine is made of cylindrical shape in transverse section and is divided internally into cells or compartments some of which are employed for the aerostats and others for the machinery and cabins or the like for the crew and for passengers, and it consists in making the skin or shell of the machine 15 either wholly or partially of sheets of what is known as multi-ply wood which is not only lighter than metal but also has a certain degree of flexibility which enables a certain amount of flexion of the structure to 20 take place without damage, while from the nature of the construction of such wood it is practically air and water-proof, and can be made absolutely so either during the course 25 of manufacture or afterward by coating it with a suitable paint or varnish.

In the accompanying drawing, which is diagrammatic only, Figure 1 is a view in side elevation of an air ship constructed according to the present invention, Fig. 2 is a view 35 in longitudinal section thereof. Fig. 3 is a view in plan thereof, partly in section, and Figs. 4, 5, 6 and 7 are views in transverse section on lines 1—1, 2—2, 3—3 and 4—4 Fig. 2.

40. Throughout the views similar parts are marked with like letters of reference.

The body of the machine is divided into two classes of compartments *b* and *c*, the former adapted to form or constitute the aerostats and the latter the chambers to contain the machinery and the like and the chambers forming the cabins or the like for the crew and for the passengers are so placed as to distribute the weight as evenly

as possible, each set being connected by a 50 suitable passage *d*, and a keel may be provided to keep the machine from rolling. Suitable doors such as *e* are provided to give direct access to each of the chambers *c*, or a single door giving access to a common passage 55 may be employed.

The frame of the machine may be constructed in any suitable manner as this forms no part of this invention, neither does the method of propelling and steering the 60 machine in which the usual construction and arrangements may be followed, the details shown in the drawing being merely by way of illustration.

The skin or shell *a* is made of sheets of 65 multi-ply wood which is secured to the framework and the joints of which are made by any of the well-known methods employed in the use of this particular wood. Multi-ply wood is not only as light as metal but 70 has the great advantage that it is more flexible and elastic and therefore better able to resist successfully the strains and stresses to which the bodies of these machines are subject without deformation or fracture, and is 75 moreover from the nature of its construction practically air and water-proof, and can be made absolutely so either during the course of manufacture or subsequently by coating it with a suitable paint or varnish. 80

What I claim as my invention and desire to secure by Letters Patent is:—

In an aerial machine a body of circular shape in cross section the skin of which is constructed of the commercial product 85 multi-ply wood and the interior of which is divided into a number of cells or compartments some of which are adapted to form or contain the aerostats and others of which are adapted to contain the machinery or to 90 form cabins for passengers.

In testimony whereof I have signed my name in the presence of two subscribing witnesses.

WILLIS STETSON WILLIAMS.

Witnesses:

A. MULWARD HACK,
ALBERT S. MICKHIN.
